(57) **CLAIM**

The ornamental design for a therapeutic sleep mask, as shown and described.

DESCRIPTION

FIG. 1 is a top-front-left perspective view of a therapeutic sleep mask showing my new design;

FIG. 2 is a bottom-rear-right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is an enlarged right elevational view thereof;

FIG. 8 is an enlarged left elevational view thereof;

FIG. 9 is an enlarged cross-sectional view taken along line 9-9 in FIG. 4; and,

FIG. 10 is a cross-sectional view taken along line 10-10 in FIG. 8.

The broken lines shown in the drawings of FIGS. 1-4 and 7-9 are included for the purpose of illustrating portions of the therapeutic sleep mask that form no part of the claimed design. The dot dash lines in FIG. 4 and FIG. 8 designate the cross-sectional views and form no part of the claimed design.

1 Claim, 10 Drawing Sheets
